KIRK S. BLANCHARD, OF BROOKLYN, NEW YORK.

FLUSH-TANK.

1,114,576.

Specification of Letters Patent.

Patented Oct. 20, 1914.

Application filed February 18, 1913. Serial No. 749,104.

To all whom it may concern:

Be it known that I, KIRK S. BLANCHARD, of Brooklyn, in the county of Kings, in the State of New York, have invented new and useful Improvements in Flush-Tanks, of which the following, taken in connection with the accompanying drawings, is a full, clear, and exact description.

This invention relates to certain improvements in flush tanks for water closets and more particularly to the ventilation as associated with the flushing device and controlling means for the water supply.

One of the objects is to provide a portion 15 of the bottom and one of the upright sides of a one piece tank with a double wall so as to form an integral ventilating chamber without seams or joints and to reduce the liability of leakage to a minimum and at the 20 same time afford a suitable chamber for the reception of a ventilating fan adapted to be driven by a water motor within the tank and operated by the inflowing water supply to the interior of the tank.

Another object is to incorporate within 25 the tank a suitable valve case containing separate valves for controlling the supply of water to the motor independently of that which controls the main water supply for 30 the tank so that the ventilating motor may be operated independently of the float-controlled supply valve.

A further object is to provide simple 35 means for holding the flush valve open when operated from its normal position until the water is practically discharged from the tank and to automatically trip the holding means when the water in the tank reaches its lowest level.

Other objects and uses will be brought out 40 in the following description.

In the drawings—Figure 1 is a vertical 45 sectional view of my improved flush tank and mechanism contained therein, showing also a portion of the bowl and seat in elevation, partly in section. Fig. 2 is a top plan of the flush tank and mechanism therein and also the rear portion of the bowl and seat to which the tank is connected, a portion 50 of the cover of the tank being broken away. Fig. 3 is an enlarged detail sectional view through a portion of the valve case in the tank, showing the valve and passage for controlling the supply of water to the 55 fan motor. Fig. 4 is an enlarged sectional view of the flush valve and a part of its op-

erating mechanism together with the adjacent portion of the tank taken on line 4—4, Fig. 2. Fig. 5 is an enlarged transverse vertical sectional view through a portion of the tank and valve case therein taken on line 5—5, Fig. 2. Fig. 6 is an enlarged longitudinal sectional view of one end of the tank showing the ventilating chambers and fan and also the motor and valve case taken on line 6—6, Fig. 2. Fig. 7 is an enlarged transverse sectional view through one end of the tank taken on line 7—7, Fig. 2. Fig. 8 is an enlarged detail sectional view through the rear end of the bowl taken on line 8—8, Fig. 2, showing a portion of the ventilating flue communicating with the interior of said bowl. Fig. 9 is a sectional view similar to Fig. 8 of a slightly modified form of ventilating flue as applied to old bowls.

In order that my invention may be clearly understood, I have shown a portion of a bowl —1— as connected by a flush pipe —2— and ventilating pipe —3— to the bottom of a flush tank —4—, the bowl being provided with a suitable seat —5— which is hinged at —6— to brackets —7— rising from the upper side of the bowl. This bowl may be of any suitable construction except 50 that the upper rear portion thereof is provided with a forwardly and rearwardly extending ventilating channel or flue —8— leading from the interior of the bowl and preferably communicating with the space 55 between the upper surface of the rim of the bowl and lower face of the seat, said channel being located above and separate from the adjacent end of the flush pipe —2— and is of considerable cross sectional area, 60 as shown in Fig. 8, for the reception of the adjacent end of the ventilating pipe —3—.

One end of the flush pipe —2— is connected to the bowl in the usual manner while the opposite end is connected by a union or 65 coupling member —9— to an externally threaded boss —10— which is secured to and extends downwardly some distance from the bottom of the tank as shown more clearly in Fig. 4.

The hollow boss —10— forms a continuation of the flush pipe —2— leading to the interior of the tank and extends upwardly a sufficient distance into the interior of said tank to form a valve seat —11— for the 70 flush valve —12—, the portion of the boss which is within the interior of the tank be-

ing provided with a refill passage below the valve seat to establish communication between the interior of the flush pipe and overflow pipe —14— as shown more clearly in Figs. 1 and 4.

The valve —12— is connected by a link —15— to one end of a lever —16— which is pivoted at —17— to a collar —18— on the overflow pipe —14— and its other end is pivotally connected to the lower end of an upright link —19— having its upper end pivotally attached to a sliding plate —20—, as shown in Fig. 7, some distance above the water line or upper end of the overflow pipe —14—.

An upright operating rod —21— is connected at its upper end to the sliding plate —20— and has its lower end extending through the bottom of the ventilating chamber of the tank and provided with a lateral forwardly projecting offset —22— extended upwardly at the front of the tank through a suitable guide way —23— terminating in a hand piece —24— at the front of the tank near one end and within easy reaching distance of the seat of the bowl so that by depressing the hand piece —24—, similar movement will be transmitted to the link —19— and adjacent end of the valve lever —16— for raising or opening the flush valve —12—.

The tank —4— is preferably made in one piece of cast metal and is divided interiorly into separate non-communicating chambers or compartments —25— and —26—, one of which, as the compartment —25—, is considerably smaller than the other compartment —26— and constitutes what may be termed a ventilating chamber, while the other larger compartment is adapted to contain water for flushing purposes.

The ventilating chamber or compartment —25— is, preferably, formed by making portions of the bottom and one of the upright sides or ends of the tank hollow or double-walled so as to communicate at their junctions one with the other, as shown more clearly in Figs. 5 and 6, the upper end of the upright portion of the ventilating chamber —25— being enlarged to receive a rotary fan —27—, as shown in Fig. 6, and is provided with an outlet —28— adapted to be connected to any ventilating flue leading to the exterior of the building but not necessary to herein illustrate or describe.

The lower horizontal portion of the ventilating chamber —25—, formed by the hollow bottom wall of the tank, extends lengthwise of said tank from one end to a point directly in front of the flush valve —12— where it communicates through an inlet passage —29— with the conduit —3— leading to the interior of the bowl —1— as shown more clearly in Fig. 1. The fan chamber, therefore, constitutes part of the

ventilating chamber and is disposed in the upper portion of the tank near one end but above the water line, while the opposite or lower end of the chamber, it is evident is below the low water level but, as previously stated, is cut off from communication with the water chamber —26— by the inner walls of the chamber —25—, the top of the tank being preferably closed by a suitable cover —30—.

The fan —27— is driven by a coaxial water motor —31— which, together with the fan, is mounted upon opposite ends of a horizontally disposed shaft —32—, the latter being journaled in a sleeve —33— extending through an opening in the inner side of the fan chamber and rigidly secured thereto to form a water and air tight joint as shown in Fig. 6.

If desired the upper side of the ventilating chamber may be closed by a suitable cap —34— which extends downwardly at the inner side of the motor to properly house said motor and prevent splashing of the water through the top of the tank and at the same time permitting it to be discharged at the bottom into said tank. This cap may be secured in place by any suitable fastening means, as screws —35—, and is provided with an inlet —36— for receiving water under pressure through the supply pipe —37—, the latter being connected to a valve case —38— within the tank. This valve case contains two valves —39— and —40— and a rock shaft —41— as shown more clearly in Figs. 5 and 6 and is connected by a slip joint —42— with one end of a branch water supply pipe —43— having its opposite end inserted in an opening —44— in the bottom of the tank as shown in Fig. 5, said opening being connected to a main supply pipe —45— by slip connection —46—.

The valve —39— controls the flow of water through an outlet —47— in the interior of the tank and is operated by means of a float lever —48— which is pivoted at —49— to a pendant boss beneath the valve and is connected intermediate its ends by a link —50— to said valve.

A float —51— is secured to the free end of the lever and adapted to be operated by the rise and fall of the water within the tank to control the opening and closing of the valve —39— in a manner somewhat similar to that set forth in my pending application No. 724,167, filed October 5, 1912.

The valve case —38— is provided with a branch passage —52— communicating with the main passage and controlled by the valve —40— which controls the flow of water or other motive fluid to the motor.

The valve —40— is pivotally connected to the intermediate portion of a lever —53— which extends lengthwise of the shaft —41— and has one end pivoted to an arm —54—

—54— on the valve case and its other end adapted to ride upon the periphery of a cam —55— on the adjacent end of the rock shaft —41— so that when the shaft is rotated in one direction, the cam —55— will elevate the adjacent end of the lever —53— and thereby lift the valve —40— from its seat to allow the water to pass from the main passage into the branch passage —52— and thence to the motor for operating the latter.

10 The rock shaft —41— may be operated by the depression of the seat —5— through the medium of a seat-operated lever —56— which is pivoted at —57— to one side of the bowl as shown in Fig. 2 and has its forward end extending under and against the seat —5— and its rear end pivotally connected with a loss motion to a crank arm —58— on one end of a rock shaft —59—. 15 This rock shaft is journalled in suitable bearings —60— on the underside of the bottom of the tank and has its opposite end provided with a crank arm —61— which is pivotally connected to a yoke —62— on the lower end of a vertically movable rod —63—, the latter extending through an opening in the bottom of the upright portion of the ventilating chamber —25— as shown more clearly in Fig. 6.

20 Secured to the upper end of this rod —63— is a laterally projecting arm —64— which is pivotally connected with a loss motion to a crank arm —65— and on the end of the rock shaft —41— opposite that to which the cam —55— is secured. It, therefore, follows that any depressions of the bowl seat from its normal position, would cause a corresponding depression of the front end of the lever —56—, thereby elevating the rod —63— and rocking the crank —65— upwardly to rotate the shaft —41— and its cam —55— for the purpose of opening the valve —40— and operating the motor as previously described.

25 Both of the vertical rods —21— and —63— for effecting the operation of the flush valve and motor respectively are passed through apertures in the bottom of the upright portion of the ventilating chamber and the lateral offsets of said rods are passed through vertically elongated apertures in the upright walls of said chamber, said apertures being of sufficient vertical length to permit the required vertical movement of the rods as shown more clearly in Figs. 6 and 7, but in each instance the side of the opening exposed to the water chamber may be closed by sliding plates as —20—.

30 It is desirable in this class of flush tanks to provide means for holding the flush valve open until the water is discharged to the lowest level from the tank and for this purpose I have provided a weighted detent or pawl —65— having its upper end

pivoted at —66— to a suitable bracket —67— on the collar —18— while its opposite end is passed through an opening in the lever —16— and provided with a weight —68— having a rounding cam face for co-action with a stud or pin —69— on an auxiliary float lever —70— as shown in Figs. 1, 2, 4 and 7.

An auxiliary float lever —70— is pivoted at —71— to the collar —18— below 75 but in close proximity to the lever —16— and extends laterally some distance therefrom for supporting at its free end a float —72— near the bottom of the tank.

The detent —65— is provided with a 80 catch or shoulder —73— positioned so as to engage and lock the flush valve lever in position for holding the flush valve open when it is opened voluntarily by the depression of the operating member —24—.

85 While the flush valve is closed, the auxiliary float —72— is held up by its own buoyancy, thereby holding the pin or stud —69— out of contact with the adjacent cam —68— on the lower end of the detent 90 —65— but as soon as the flush valve is opened allowing the detent —65— to interlock with the lever and to hold the valve in its open position, the recession of the outflowing water to its lowest level allows 95 the auxiliary float —72— to drop, thereby bringing the stud or pin —69— into engagement with the cam —68— to trip the detent and allow the flush valve to close by its own gravity, thus returning the lever 100 —16— and its operating mechanism to normal position. It is evident, however, that during this recession of the water in the tank, the float —51— drops by its own gravity to open the valve —39— and allow 105 the tank to refill, the closet bowl being refilled through a refill pipe —80— leading from the discharge opening —47— into the upper end of the overflow pipe —14— from which such refilled water passes into the 110 flush pipe through the passage —13—, Fig. 4.

115 In Fig. 8, I have shown a ventilating chamber —8— as formed in the bowl, but in old closets, I may use an extra cap or cover —8— as shown in Fig. 9, coöperating with the top of the bowl to form the desired ventilating space.

The operation of my invention will now be readily understood upon reference to the 120 foregoing description and the accompanying drawings and it is evident that various changes may be made in the bowl construction and arrangement of the several parts without departing from the spirit of this 125 invention.

What I claim is:

1. A flush tank for water closets having an interior partition running horizontally along the bottom and vertically along one 130

end and united to said bottom and end to form a ventilating chamber separate from the remaining interior space, a vent pipe leading from the ventilating chamber, a fan in said chamber, and driving means for the fan.

2. A flush tank for water closets having an interior partition running horizontally along the bottom and vertically along one end and united to said bottom and end to form a ventilating chamber separate from the remaining interior space, a vent pipe leading from the ventilating chamber, a fan in said chamber, a shaft for the fan extending through the upright portion of the partition, a water-motor secured to the inner end of the shaft, a flush pipe and a water supply pipe both leading from the interior of the tank separate from the ventilating chamber, a flush valve for the flush pipe, a ball cock for the supply pipe discharging into the tank and provided with a separate outlet leading to the motor, a valve for the separate outlet, and means for operating said valve.

3. In combination with a water-closet bowl having an air vent leading from its interior, a flush tank having a partition extending along and near its bottom and one end and united thereto to form a ventilating chamber separate from the remaining space in the tank, a vent pipe connecting

the bowl-vent with said chamber, a delivery pipe leading from the chamber, a fan in said chamber, a water motor for the fan, a flush pipe and a water supply pipe both leading from the interior of the tank separate from the ventilating chamber, the flush pipe being connected to the bowl, a valve for the flush pipe discharging into the tank and provided with a separate outlet leading to the motor, a valve for said outlet, and means having portions thereof extending through the ventilating chamber for operating said valve.

4. In combination with the bowl of a water closet, a low-down tank at the rear and just above the top of the bowl, a flush pipe leading from the rear end of the bowl into the bottom of the tank, and a vent pipe leading from the bowl directly above the adjacent end of the flush pipe and entering the bottom of the tank directly in front of the flush pipe, said tank having a ventilating chamber therein separate from the remaining water space and communicating with the vent pipe.

In witness whereof I have hereunto set my hand this 10th day of February, 1913.

KIRK S. BLANCHARD.
